UNITED STATES PATENT OFFICE.

CHARLES O. COONS, OF SPRINGFIELD, ILLINOIS.

DRIVING MECHANISM.

1,276,622.

Specification of Letters Patent. Patented Aug. 20, 1918.

Application filed January 29, 1916. Serial No. 75,184.

To all whom it may concern:

Be it known that I, CHARLES O. COONS, a citizen of the United States, residing at Springfield, in the county of Sangamon and State of Illinois, have invented certain new and useful Improvements in Driving Mechanism, of which the following is a specification.

This invention relates to a driving mechanism and more particularly has for its object the provision of an improved mechanism wherein an invariable speed is constantly furnished.

The primary object of the invention, resides in the provision of mechanism wherein driving and driven members are supplied, with means for connecting the said members, the means being automatically adjusted so that any variation in the speed of the driving members may be compensated for.

It is also contemplated by the construction to provide a novel driving mechanism, which may be adapted for operating the shutter of a motion picture projector, wherein, it is especially desirable, that the said shutter be operated at a uniform speed, in order to prevent the noticeable flickering.

All of the foregoing together with additional advantageous details and arrangements of the parts of the preferred embodiment of my invention will be clear from the specific description hereinafter contained, when read in connection with the accompanying drawings forming a part thereof, wherein said embodiment of the invention is illustrated for the purpose of facilitating a full understanding of the present improvements.

Referring to the drawings,

Figure 1 is a side elevation showing the arrangement of the various gearings and partly in section.

Fig. 2 is a horizontal section taken through the mechanism.

Fig. 3 is a detail view partly in section taken on the line 3—3 of Fig. 1, and

Fig. 4 is a fragmentary view in detail and partly in section taken on the line 4—4 of Fig. 1.

Referring now more particularly to the drawings, and in connection with which like reference characters refer to corresponding parts throughout the several views thereof, 1 is a base for supporting a frame member 2 provided with leg portions 3 and 4,

which are secured to the base, as shown at 5 and 6 by suitable fastening devices and 7 is a vertical standard formed integral with the frame having a bifurcated portion 8 arranged thereon, the purpose of which shall be hereinafter described.

9 is a main driving gear carried by a shaft 10 arranged transversely of the frame 2 and provided with a squared end portion 10' and supported in suitable bearings as at 11 therein, the gear wheel being keyed to the shaft by means of a screw 12 or other securing means, passing through a collar 13 formed upon the gear 9. Positioned adjacent the gear 9 and keyed to the shaft 10, in some suitable manner, is a bevel gear 14 and adapted for rotation therewith.

Supported in bearings 15 arranged upon one end of the bifurcated portion 8, is a shaft 16 having keyed thereto a bevel gear 17, which is positioned adjacent the bevel gear 14 and constantly in mesh therewith. In order to provide for speed governing means I position a centrifugal governor shown in 18 an entirety at 18 upon the shaft 16, the same being provided with a sliding collar 19, keyed to the shaft as shown at 20, the key traveling within an elongated groove 21 formed in the shaft 16 so as to allow for vertical movement of the collar and also to connect the same for rotation with the shaft. The collar has pivotally secured thereto by means of ears 22 the conventional form of weighted members 23 used in connection with a centrifugal speed governor. 24 is a collar portion formed integral with one end of the shaft 16 and is also provided with ears 25, similar to those as shown at 22, for pivotally connecting the weighted members 23 therewith. 26 is an elongated slot arranged in the shaft 16, the shaft being provided with a coaxial bore 27 threaded interiorly, the said bore communicating with the elongated slot 26 and arranged centrally of the collar portion 24. 28 is a thumb screw adapted to be received or turned into engagement with the interiorly threaded bore, and having arranged at one end thereof a cross piece 29, which is received within the elongated slot 26 and movable therein, and 30 is a coiled spring arranged about the shaft 16, one end thereof bearing against the cross piece 29 and the remaining end in engagement with the slideable collar 19. It may be also mentioned that a series of graduations 31 may be placed upon the

shaft 16 adjacent the elongated slot 26, so as to enable the operator to provide for a predetermined tension upon the spring 30, by adjusting the thumb screw 28.

5 Pivottally mounted within the bearings, as shown at 32 upon the remaining end of the bifurcated portion 8, is a cylindrical body 33 having arranged therein and parallel thereto, a squared bore 34. 35 is a yoke member 10 having an arm 36 extending therefrom, the same being of a shape to conform to the bore 34, while the yoke member 35 is pivotally secured to the slidable collar 19, as shown at 38, and is so connected therewith as to 15 allow for the rotation of the collar 19, by means of the usual form of circumferential collar 39 which is held in slidable relation with the collar 19 by means of a tongue portion 40. 41 is a squared arm received 20 in the remaining end of the bore 34, and provided with a similar bifurcated yoke member 42 which is connected in a like manner, with a collar 43, to be subsequently described.

25 44 is a gear of smaller diameter than the gear 9, rotatably mounted upon a shaft 45 and held thereto by the insertion of screws 46 through the collar 47 arranged integral with the gear 44, the gear 44 being in constant mesh with the larger gear 9. Positioned adjacent the gear 44 is a friction disk 48, secured to the shaft 45 by the passing of fastening means through the collar 49 arranged thereon. Mounted in suitable bearings 50 and adjacent the friction disk 48 is a vertical shaft 51 having arranged therein an elongated groove 52, and keyed to its outer end a bevel gear 53. 54 is a frictional gear having formed thereon a collar portion 43 and slidably keyed to the shaft 51 through the medium of a key 55 which travels within the elongated groove 52. The collar 43 is provided with a second circumferential yoke member 56, similar to the member 39, to which the bifurcated yoke portion 42 is 45 pivotally secured, as at 57. It may be mentioned, that the vertical shaft 51 is supported in position by means of an arm 58 secured to a supporting wall 58', having 50 arranged therein a bearing 59. Formed integral with the arm 58 is an angular bracket portion 60 having a bearing part 61, in which is rotatably supported a bevel gear 62, constantly in mesh with the bevel gear 53. 55 Coming now to the operation of the device, a crank or other similar member is applied to the squared portion 10' of the shaft 10 and when rotated will cause the gear 9 to be carried therewith, consequently 60 causing the gear 44 and frictional disk 48 to be also rotated, thereby rotating the frictional gearing 54 which is in engagement with the friction disk 48, transmitting motion to the bevel gear 62 which is connected 65 with the device to be operated. Thus, it

will be seen that the direct drive is through the gear 9 to the gear 44, thence to the friction disk 48, whereupon it is transmitted to a friction gear 54 and then through the bevel gear 53 to the operating gear 61. Referring 70 now to the speed governing mechanism, it will be noted that the bevel gear 17 is in mesh with the gear 14, which is in turn keyed to the shaft 10. The operator when desiring a certain speed, adjusts the thumb screw 28 75 either upward or downward, thereby regulating the tension of the spring 30, the amount of the tension being ascertained by means of the graduations 31, consequently applying the necessary pressure to the collar 19 of the 80 centrifugal governor. Assuming that the shaft 16 is being rotated at an exceedingly rapid speed, due to the operation of the driving gear 14, and that the speed is such as to be in excess of the amount desired by the 85 operator and of the predetermined adjustment, it is apparent, that the weighted members 23 of the governor will be thrown outwardly by the centrifugal force of the rotation, causing the collar 19 to be moved upwardly against the tension of the spring 30 thereby causing the frictional gear 54 to be carried to a position near the center of the friction disk 48, thus decreasing the speed 95 of the drive from the friction disk 48 to the friction gear 54 and consequently allowing for a constant speed. If it should be that the shaft 16 is rotated at a speed less than that desired, it is obvious, that the spring 30 will force the collar 19 of the governor back 100 upon the shaft 16 against the centrifugal force offered by the weighted members 23, and in this instance, allows the friction gear 54 to be adjusted to a position near the periphery of the friction disk 48, through the 105 connections 34, 36 and 41, and thereby compensate for the decreased rotation of the driving gear 9.

From the foregoing, it will be appreciated, that I have provided a driving mechanism 110 which might be adapted for operating any construction where it is desired to obtain an unvarying speed of driving power and further, a device wherein the rotation of the prime mover may be varied without affecting 115 the speed of the driving means. This construction, of course, is particularly adapted to be used in conjunction with the manually operated motion picture projectors, wherein the operator's attention is often directed to various other matters, consequently allowing the driving means of the projector to be rotated slower, which causes the shutter of the projecting apparatus to be moved at a decreased speed, causing the objectionable flickering of the pictures, and further, that the film feeding device will also be operated at a decreased speed causing 120 the pictures to be projected in an unnatural manner.

Having thus described the invention what I claim is:

1. Power transmitting mechanism, including a driving member, a driven member intergeared with said driving member, a disk carried on and driven by said driven member, a power transmitting shaft arranged parallel to one surface of said disk, a slideable friction gear mounted on said shaft, 10 governor means driven from said driving element, a pivotal adjustable rod connected with said governor means and said gear whereby the gear will be automatically shifted upon movement of the governor means 15 to various positions of engagement with said disk for transmitting power at a uniform velocity, and means engaged with said governor means for adjusting the same.
2. A power transmitting mechanism including a driving member, a driven member intergeared with said driving member, a disk carried on and driven by said driven member, a power transmitting shaft arranged parallel to one surface of said disk, 25 a slideable friction gear mounted on said shaft, governor means driven from said driving element, a pivotal body having a central bore extending therethrough, an arm slidably mounted in each end of said body, 30 means connecting said arm to said governor means and said gear, whereby the gear will be automatically shifted upon movement of the governor means to various positions of engagement with said disk for transmitting power at a uniform velocity, and means engaged with said governor means for adjusting 35 the same.
3. A power transmitting mechanism including a driving element, a driven member 40 intergeared with said driving element, a disk carried on and driven by said driven member, a power transmitting shaft arranged parallel to one surface of said disk, a slideable friction gear mounted on said shaft, 45 governor means driven from said driving element, a pivotal body having a bore extending therethrough, arms slidably mounted in the ends of said bore, and engaging said governor means of said gear, 50 whereby the gear will be automatically shifted upon movement of the governor means to various positions of engagement with said disk, for transmitting power at a uniform velocity.
4. A power transmitting mechanism including a driving element, a driven member intergeared with said driving element, a disk carried on and driven by said driven member, a power transmitting means arranged 55 parallel to one surface of said disk, a slideable friction gear mounted on said shaft, 60 governor means driven from said driving element, a pivotal adjustable rod connected

with said governor means and said gear whereby the gear will be automatically shifted 65 upon movement of the governor means to various positions of engagement with said disk, for transmitting power at a uniform velocity, a spring bearing upon said governor means, and a set screw carried by said 70 spring for adjusting the tension thereof.

5. A power transmitting mechanism including a main gear, an auxiliary gear intermeshed therewith, a friction plate driven by said auxiliary gear, a shaft adjacent said 75 friction plate, a friction gear slideable on said shaft and engaging said friction plate, a governor shaft carried adjacent and driven by said main gear, a governor element mounted upon said last mentioned 80 shaft, a screw carried by said last mentioned shaft, a spring bearing upon said governor means, a plate carried by said last mentioned shaft and held in engagement with said spring by said set screws for allowing the 85 tension of said spring to be adjusted for adjusting said governor means, and means connecting said governor means to said friction disk for automatically transmitting power at a uniform velocity. 90

6. A power transmitting mechanism including a driving means and a driven means, a governor means connected to said driving means, a pivotal body having a bore extending therethrough, arms slidably mounted in 95 the ends of said bore and engaging said governor means and said driven means, whereby said driven means will be automatically operated upon movement of the governor means by movement of said body and 100 arms, thus transmitting power at a uniform velocity.

7. A power transmitting mechanism including a driving means and a driven means, a governor means connected to said driving 105 means, a shaft carried adjacent said driving means, said shaft having a longitudinal slot, a set screw carried by said shaft and projecting into said slot, a spring bearing upon said governor means, a plate carried within 110 said slot and held in engagement with said spring by said set screw for allowing the tension of the said spring to be adjusted for adjusting said governor means, and means connecting said governor means to 115 said driven means and coöperating with said governor means and driven means for automatically transmitting power at a uniform velocity.

In testimony whereof I affix my signature 120 in presence of two witnesses.

CHARLES O. COONS.
